Primary Examiner — Michelle E. Wilson*Assistant Examiner* — Amanda J Berlinski(74) *Attorney, Agent, or Firm* — Betsy Kingsbury Dowd, Esq; BKDowd Law, P.C.(57) **CLAIM**

The ornamental design for a breast shield cap, as shown and described.

DESCRIPTION

FIG. 1 is a front and top perspective view of a breast shield cap, in use mounted on a breast shield, depicting my new design;

FIG. 2 is a front and top perspective view of the breast shield cap depicted in FIG. 1;

FIG. 3 is a top view of the breast shield cap depicted in FIG. 1;

FIG. 4 is a bottom view of the breast shield cap depicted in FIG. 1;

FIG. 5 is a cross sectional view of the breast shield cap depicted in FIG. 1 taken from the line 5-5 in FIG. 3;

FIG. 6 is a left view of the breast shield cap depicted in FIG. 1, the right view being a mirror image thereof;

FIG. 7 is a front view of the breast shield cap depicted in FIG. 1, the back view being a mirror image thereof; and,

FIG. 8 is a front and bottom perspective view of the breast shield cap depicted in FIG. 1, in use mounted on a breast shield.

The broken line showing of a part of a breast shield in FIG. 1 and FIG. 8 depicts environmental structure that forms no part of the claimed design.

1 Claim, 4 Drawing Sheets(56)
